US0D1043790S

(12) **United States Design Patent** (10) **Patent No.:** **US D1,043,790 S**
(45) **Date of Patent:** **** Sep. 24, 2024**

(54) **HANDHELD THERMAL IMAGER**

(71) Applicant: **Hangzhou Microimage Software Co., Ltd.**, Zhejiang (CN)

(72) Inventor: **Dingsong Lin**, Zhejiang (CN)

(73) Assignee: **Hangzhou Microimage Software Co., Ltd.**, Zhejiang (CN)

(**) Term: **15 Years**

(21) Appl. No.: **29/847,245**

(22) Filed: **Jul. 22, 2022**

(30) **Foreign Application Priority Data**

Jan. 24, 2022 (CN) 202230049437.X

(51) **LOC (14) Cl.** **16-05**

(52) **U.S. Cl.**

USPC **D16/219**; D16/206

(57) **CLAIM**

The ornamental design for a handheld thermal imager, as shown and described.

DESCRIPTION

FIG. 1 is a front view of a handheld thermal imager showing my new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a top, front and left perspective view thereof; and, FIG. 8 is an alternate top, front and left perspective view thereof.

The broken lines shown in FIGS. 1-8 are included for the purpose of illustrating portions of the handheld thermal imager that form no part of the claimed design. The dot-dash lines denote the boundary of the claim and form no part of the claimed design.

1 Claim, 8 Drawing Sheets
